UNITED STATES PATENT OFFICE.

DONLEY C. HENNEN, OF WAYNESBURG, PENNSYLVANIA, ASSIGNOR OF ONE-HALF TO
CHARLES L. MONG, OF WAYNESBURG, PENNSYLVANIA.

SANITARY TOOTH-BRUSH HOLDER.

1,257,860.

Specification of Letters Patent. Patented Feb. 26, 1918.

Application filed September 19, 1917. Serial No. 192,154.

To all whom it may concern:

Be it known that I, DONLEY C. HENNEN, a citizen of the United States of America, residing at Waynesburg, in the county of Greene and State of Pennsylvania, have invented certain new and useful Improvements in Sanitary Tooth-Brush Holders, of which the following is a specification.

This invention relates to improvements in sanitary tooth brush holders.

The primary object of the invention is to provide simple and inexpensive means for supporting a tooth brush and protecting same from germ contamination, means being provided for inclosing the brush portion, and also to admit sufficient air to insure proper ventilation.

The invention also comprehends improvements in the details of construction and arrangement of parts which will be herein-after described and particularly pointed out in the claims.

In the accompanying drawings:—

Figure 1 is a perspective view of my improved brush holder.

Fig. 2 is a vertical section of same but illustrating a slightly different form of the invention.

Fig. 3 is a bottom plan view of the holder shown in Fig. 1.

Fig. 4 is a perspective view of a further development of the invention.

1 indicates a bracket, preferably stamped from sheet metal, and formed with a wall member 2, and a horizontal support 3. The horizontal member 3 is formed with an annular opening 4, and extending therethrough is a glass container 5, closed at its upper end and provided at its lower end with an annular flange 6. Fitted snugly against the under side of the horizontal member 3, is a flat plate 7, formed with an opening 8, which registers with the open lower end of the container 5. The rear wall of the opening 8, is formed with a preferably dovetail notch 9, as clearly shown in the drawing.

In Fig. 1 the edge of the horizontal member 3 is extended to provide a retaining flange 10, bent around the edge of the plate 7, and crimped to hold the parts together. In Fig. 2 the retaining flange is dispensed with, and the plate 7 is soldered or otherwise secured to the horizontal member 3.

The upper surface of the annular flange 6, of the container snugly engages the under surface of the horizontal member 3, surrounding the opening 4, while the bottom of the flange 6, is engaged by the plate 7, and as said plate is secured to the horizontal member, an effective and simple means is provided for fastening the parts together.

Pivoted to the underside of the plate 7 is a closure 11 adapted to close the opening 8, when a tooth brush is supported in the holder. The closure is provided with perforations for the admission of air to the container, which of course prevents a damp brush from becoming foul.

In the form of the invention shown in Fig. 4, the bracket 13 is shown elongated, and in the opening 14 is an elongated glass container 15, which is provided with partition 14^a, to form separate containers for the brush. The plate 16 is made of sufficient length to extend the length of the horizontal portion of the bracket, and it is provided with a plurality of brush openings 17, each having a dovetail notch in the rear wall.

Obviously by employing this construction provision is made for a plurality of brushes in a single container.

In lieu of the container being made elongated as shown in Fig. 4, the single bracket may be formed with separate openings to correspond with the number of openings in the plate 16.

In use, the bracket is attached to a convenient place on the wall or other support, and to insert a tooth brush the closure is swung to one side to uncover the opening 8. The head of the brush is then inserted through the opening 8, and up into the container 5. The small part of the brush handle is now slipped into the notch 9 and given a slight turn, and the dovetail walls serve to hold it against falling. The closure is now turned to cover the opening 8, air for ventilating the interior of the container passing through the perforations 12.

From the foregoing description, it will be seen that I have constructed a neat, practical, inexpensive, and sanitary means for supporting a tooth brush, and one which can be conveniently manipulated in inserting or removing a brush.

By forming the container of glass, it adds

to the neatness of the structure, and at the same time it exposes to view the opening through which the brush is inserted, which enables an operator to quickly place the 5 brush in position.

What I claim is:—

- 10 1. A tooth brush holder comprising a horizontal member formed with an opening and having part of its edge extended to form a flange, a glass container extending through the opening and having its upper end closed and formed at its lower end with a flange, a plate formed with an opening which registers with the bottom of the container, and 15 fitted to the underside of the horizontal member to hold the flange container in position, the flange on the horizontal member being bent over and under the edge of the plate to fasten the latter to said member, 20 and a pivoted perforated closure on the under side of the plate to cover the opening in the

latter when a brush is inserted in the container.

2. A tooth brush holder comprising a bracket having a horizontal member formed 25 with an opening, an inverted container extending through the opening and closed at its upper end and provided at its lower end with a flange, the latter engaging the underside of the horizontal member, a plate fitted 30 to the underside of the horizontal member and extending over the flange of the container to hold the latter in position on the bracket, means for securing the plate to the horizontal member, said plate having an 35 opening which registers with the container, and a perforated movable closure for closing the openings in the plate when a tooth brush is inserted in the container.

In testimony whereof I affix my signature. 40

DONLEY C. HENNEN.
